Application August 12, 1947, Serial No. 768,124

7 Claims. (Cl. 101—163)

1

This invention relates to a printing and embossing machine, and, in particular, to a press for the running of intaglio plates and dies in embossing and printing.

More specifically, this invention relates to presses on which intaglio printing and embossing is done by means including a plunger or similar element moving up and down to produce the required pressure of the paper against a die or plate.

One of the problems associated with such printing machines is the difficulty of providing satisfactory, adjustable, and controllable means for producing the proper amount of pressure of the paper against the plate or die with each impression. Due to the fact that heavy pressure is required, especially with fine engraving and embossing, and to the fact that intaglio printing and embossing is done on paper of various textures, weights or thicknesses, it is necessary not only to be able to make fine adjustments in the positioning of the plunger, or other element by which the paper and the die or plate are pressed into impression-making contact, but also to guard against increasing the pressure, as a result of such adjustments, to the point where damage or danger occurs. It is not unusual for the heads or plunger supports in intaglio presses to become cracked and otherwise permanently damaged as a result of insufficient care in making such adjustments and permitting a pressure to be developed which even the customary massive frames of such presses cannot stand. Other difficulties also arise with excessive pressure even if the press is not actually damaged.

An object of the present invention is to provide a press having novel and improved means whereby fine adjustments in the positioning of the plunger element can easily be made.

A related object is to provide associated means for preventing destructive pressure, or any pressure in excess of a predetermined maximum, being set up in spite of carelessness in making adjustments.

Another object of this invention is to provide an improved press which can quickly be set to produce the exact pressure desired for intaglio printing or embossing with a particular die or "make-ready press."

A further object of this invention is to provide an improved press of the character described in which the plunger or moving pressure-producing elements, by which the paper and die or plate are momentarily pressed against each other, will be located below the die instead of

2

above it, enabling the tracks on which the carriage for the die or plate is mounted to be spaced on each side of the die carriage anvil. There are several advantages in such arrangement. It enables the upper portion of the press to be considerably reduced in size, and makes the entire machine more compact and of smaller overall dimensions. It also enables the sheet, which is to be printed or embossed, to be fed to the machine right side up and this fact, and the fact that it is not necessary to confine the paper feeding means to the usual small space left above the die or plate, facilitate the attachment and use of an automatic feeder.

15 An additional object of this invention is to provide an improved simple and practical construction for certain parts of the press as hereinafter described.

20 The manner in which these objects and advantages are attained will be apparent from the following description in which references are made to the accompanying drawings.

In the drawings:

25 Fig. 1 is an exterior view, in perspective, of my entire press, the external power drive means and power connections being omitted therefrom;

Fig. 2 is a corresponding front elevation drawn to slightly larger scale, of the press with the lower front plates of the housing removed to show part of the mechanism located therein;

30 Fig. 3 is a front elevation, drawn to a larger scale, of the same mechanism located in the housing including the plunger and the supporting and operating means associated with the plunger, with portions broken away to show the construction and arrangement of certain parts;

35 Fig. 4 is a corresponding side elevation of the mechanism taken within the housing, with portions broken away;

Fig. 5 is a fragmentary staggered vertical section on line 5—5 of Fig. 3;

40 Fig. 6 is a dissected front elevation of part of the mechanism of Fig. 3, the members being shown separated from each other for the sake of clarity but arranged more or less in their related order, this figure being drawn to the same scale as Fig. 3 and with portions shown in section for further clarity;

45 Fig. 7 is a side fragmentary elevation corresponding to line 7—7 of Fig. 3 but with the connecting cap joining the upper and lower toggle elements removed;

50 Fig. 8 is a side elevation of the emergency

toggle-throw-out lever assembly drawn to a smaller scale than Fig. 3;

Fig. 9 is a corresponding front elevation of the same lever assembly;

Fig. 10 is a front elevation, drawn on an enlarged scale, of the positioning gage for the hydraulic piston control which serves to indicate the relative maximum raised position of the plunger of my press;

Fig. 11 is a fragmentary section on line 11-11 of Fig. 10;

Fig. 12 is an enlarged vertical section taken approximately through the center of the hydraulic cylinder and associated elements comprising the lower part of the mechanism of Figs. 3 and 4;

Fig. 13 is a staggered section corresponding to line 13-13 of Fig. 12; and

Fig. 14 is a fragmentary vertical section on line 14-14 of Fig. 13.

My improved press is, for the most part, contained within a housing indicated in general by the reference character 11 in Fig. 1. Below the top or head portion of the housing 11 the front of the housing is recessed and open to constitute the throat 12 in which the actual printing or embossing takes place. A feed table platform 13 is located in the bottom of this recessed portion of throat 12 and is attached to the plunger head (to be described later). The feed table platform carries the companion pressing plate or the male portion of the intaglio plate assembly. The paper, or other material, which is being printed or embossed, is placed in position on platform 13 and then pressed against the die or plate mounted in the carriage above the platform 13.

The die or plate, indicated at 14 in Figs. 1 and 2, is slidably mounted on a pair of horizontal tracks 15 and mechanism (not shown) is provided for moving the die or plate, after the customary inking and wiping, to the forward position above the plunger head in synchronism with the movement of the plunger head so that the die or plate will be in its forward horizontal position when the plunger head presses the sheet of paper deposited on the feed table platform up against the die or plate. Then with the withdrawal of the plunger head downward the die or plate is moved back into the housing where it is again given the customary inking and wiping preparatory to being returned to the forward position for the printing of the next sheet, provided ink is being used, or, in special embossing, the die may be caused to remain in front position. While various mechanisms and devices for inking and wiping the die or plate and for moving it into operative and inoperative positions such as those now in common use on presses for intaglio printing or embossing may be employed in this machine, I have provided an improved special mechanism for this purpose which, however, will be the subject of a subsequent application for patent and with which this present application is not concerned.

The plunger assembly (Figs. 3 and 4) includes a main plunger member 16 carrying a head plate 17 and supported by upper and lower toggle members 18 and 19. The lower toggle member 19 is hingedly supported on a base block 20 which in turn is mounted on the top of a hydraulic positioning piston 21. The base block 20 ordinarily remains stationary but its position may be adjusted, that is it may be raised or lowered, by raising or lowering the supporting hydraulic piston 21, as will be explained later.

The main plunger member 16 is slidable up and down between suitable bearing blocks 22 (Figs. 3 and 4). This main plunger member comprises a heavy solid metal block preferably formed with a central chamber 23 extending inwardly from the rear wall and sealed by a rear plate 24 (Fig. 4). Oil packing is placed in the chamber 23 and the chamber is kept filled with oil which is supplied through an oiling inlet 25. Small outlet holes 26 are drilled through the bottom of the plunger member 16 into the chamber 23 to provide lubrication for the bottom of the plunger member 16, and similar small lubrication holes 27 are drilled through the rear plate 24 and through the sides of plunger member 16, to provide proper lubrication for the surfaces of the plunger member 16.

The bottom of the plunger member 16 is formed with a concave groove 28, the curvature of which corresponds to the semicylindrical top surface of the upper toggle member 18 (Figs. 4 and 5) and this groove constitutes a bearing for the top of the upper toggle member 18. The bottom of the upper toggle member 18 is formed with a central curved groove 29 (Figs. 3, 6 and 7), and the top of the lower toggle member 19 has an identical curved groove 30 similarly centrally located and similarly extending from one side of the toggle member to the other. The curvature of these grooves 29 and 30 corresponds to the radius of a shaft 31 which shaft rests in the groove 30 of the lower toggle member 19 and on which shaft the upper member 18 in turn rests. The bottom of the upper toggle member 18 slopes upwardly from each side of the groove 29, as shown in 18' in Fig. 7 and the top of the lower toggle member 19 on each side of the groove 30 similarly slopes downwardly as shown at 19' to permit the usual toggle joint movement of the members 18 and 19 without interfering with each other.

The two toggle members 18 and 19 and their mutual bearing shaft 31 are kept in operative relationship by a pair of cup-shaped caps 32 and 33 (Figs. 3 and 6) which are attached to the respective ends of the shaft 31 by screws 34 extending through the caps into threaded holes in the ends of the shaft 31. The sides of the toggle members 18 and 19 are formed with circular grooves 35 (see also Fig. 7) to accommodate the flanged rims of the cup-shaped caps 32 and 33.

A portion of the bottom of upper toggle member 18 and a similar portion of the top of lower toggle member 19 are cut away to provide space for free movement of a roller 36 which is rotatably mounted on the shaft 31. The roller 36 is adapted to have rolling contact with a rotating cam 37 (Fig. 4) secured to a shaft 38. The shaft 38 and with it the cam 37 are rotated by external power driving means (not shown). Tension springs 39 having their upper and lower ends secured to pins 39', mounted in the sides of the upper and lower toggle members 18 and 19 respectively, tend to cause the toggle members to thrust the roller 36 back and thus keep the roller 36 pressed against the perimeter of the cam 37 at all times so that roller 36 acts as the cam follower.

Thus it will be apparent from Fig. 4 that, as the cam 37 is rotated, the two toggle members 18 and 19 will move alternately away from and towards alignment with each other, the members 18 and 19 never coming into entire alignment with each other, but, when reaching their maximum extended or full line position shown in Fig. 4, coming within a few degrees of complete aline-

ment. With the base block 20 remaining stationary this movement of the toggle members towards and away from alignment produces up and down movement of the main plunger member 16 with its head plate 17.

The head plate 17 (Fig. 3) is slidably into place on the main plunger member 16 between a pair of guide bars 74 which are secured to the sides of the member 16 at the top, and the side edges of the head plate 17 are formed into a sliding fit with the corresponding grooves in the guide bars 74.

The rear wall of the groove 28 on the bottom of the plunger member 16 is of less depth than the front wall and the rear side of member 16 slopes obliquely, as indicated at 77 in Fig. 5. This is to enable the top of the upper toggle member 18 to be pushed rearwardly out of engagement with the groove 28, in case of emergency, and subsequently to be pulled back into such engagement. The circumstances under which such emergency might arise making it desirable temporarily to disengage toggle member 18 and plunger member 16 will be explained later.

A bell-crank lever 80 (Figs. 3, 8 and 9), pivotally mounted at 81 on the inside of a side wall of the housing 11, carries a roller 82 at its upper end which bears against the front face of upper toggle member 18 near the top of the toggle member. A link 83 connects the opposite end of the bell-crank 80 with a foot pedal arm 84. The arm 84 is pivotally supported on the housing 11 at 85, is movable up or down in a guideway 86, and the forward end extends out in front of the housing 11 and carries an adjustable foot pedal 87. From Figs. 3, 4, 8 and 9 it will be apparent that, if the foot pedal 87 is pressed down, the upper end of toggle member 18 will be pushed out of the groove 28 in the bottom of plunger member 16 and thus the toggle member will be temporarily disengaged from the plunger member 16. However, when pressure on the foot pedal 87 is released, the springs 89 (Figs. 3 and 4) will act to pull the upper end of toggle 18 back into the groove 28. To facilitate the pushing of the toggle end out of groove 28 and the subsequent pulling of it back into groove 28, the rear wall of groove 28 is partly cut away, as previously mentioned, and has a rounded edge (Figs. 4 and 8). When the toggle member 18 is disengaged from the plunger 16 the latter is prevented from dropping down too far by the engagement of the guide bars 74 (Fig. 3) with the bearing blocks 22.

If, while the press is operating, it should happen that no sheet of paper is in position for being pressed against the die or plate, the operator, by pressing his foot on the foot pedal 87, can quickly prevent the plunger and plunger head from being pushed upwardly even though the running of the press is not stopped, and thus prevent the head plate 17 from being pushed into direct contact with the die or plate.

The bottom end of the lower toggle member 19 has a hinge connection with the base block 20 (Figs. 3, 4 and 5). To provide for this hinge connection the bottom end of toggle member 19 is formed with a central extension 19a (Figs. 3 and 6) while the base block 20 is formed with a central recess 20a. A hinge shaft 75 extends through side portions of the base block on both sides of the central recess 20a and through the toggle member extension 19a. The opposed surfaces at the top of base block 20 and at the bottom of toggle member 19 are curved as shown at 40 and 41 respectively (Fig. 4) to permit freedom

of hinged movement of the toggle member 19 with respect to base block 20. The bottom face of base block 20 has a circular recess 42 (Figs. 5 and 12) into which the top of the hydraulic piston 21 is fitted.

The hydraulic piston 21 (see Fig. 12) is mounted for vertical movement in a hydraulic cylinder. While the hydraulic cylinder may be formed in various ways, in my preferred form of construction, as illustrated in Figs. 12, 13 and 14, the cylinder comprises a base 43 having an integral upstanding circular flange 44. The flange 44 is threaded on its inside face and these threads engage with the threads at the lower portion of the outside face of the cylindrical wall 45 which constitutes the inner wall of the hydraulic cylinder. A cylinder head 46 has a similar downwardly-extending circular flange 47 which is threaded on the inside face and the threads of which engage threads on the upper portion of the outside face of the cylindrical wall 45. An outer wall 48 extends over the outside faces of the flanges 47 and 44 and thus forms an annular closed chamber 49. The cylinder head 46 is threaded on its outer periphery and a piston-adjusting cap 50 with a downwardly-extending peripheral flange has corresponding engaging threads on the inner face of the flange so that the cap is secured in place on the cylinder head 46 and may be raised or lowered with respect to the cylinder head by turning the cap on the cylinder head.

The piston 21 (Fig. 12) has an annular shoulder 51 with a reduced diameter portion extending above the shoulder. The piston-adjusting cap 50 has a central circular opening the diameter of which corresponds to the diameter of the reduced portion of the hydraulic piston 21. Thus the cap 50 limits the upward movement of the piston 21. The outer face of the flange of the cap 50 is provided with gear teeth 52 (see also Fig. 4) which are adapted to be engaged by a worm gear 53 mounted in a support 54. The worm gear shaft extends through the lower front plate of the housing 11 and a hand wheel 55 is secured to the outer end of the worm gear shaft. Thus by turning the hand wheel 55 the piston-adjusting cap 50 can be raised or lowered on the hydraulic cylinder.

The hydraulic piston 21 has an inner central cavity 56 open at the bottom, in which is located a helical spring 57. The bottom of the spring 57 bears against the base 43 of the hydraulic cylinder, and thus the spring 57 tends to keep the piston 21 in the maximum raised position permitted by the cap 50 as shown in Fig. 12. The piston is provided near the bottom with suitable packing or sealing rings indicated at 58 to form sliding sealing contact with the inside cylinder wall 45 of the hydraulic cylinder.

Hydraulic fluid is initially supplied through the inlet channel 59 the outer end of which is connected to any suitable source of hydraulic fluid (not shown). The inner end of channel 59 discharges through a ball valve 60 into the bottom of the hydraulic cylinder. A branch passageway 72 connects the channel 59 with the annular chamber 49 (Fig. 12). Enough hydraulic fluid is initially supplied to fill the space in the hydraulic cylinder below the piston 21 and also to fill the annular chamber 49 part way. Then the outer end of channel 59 is closed with a threaded plug 79.

A safety relief valve 62 is located in the channel 61 extending from the bottom of the hydraulic cylinder, and this safety relief valve is

normally held closed by the spring 63. The spring 63 is located in a cavity 64 the outer end of which is closed by a screw plug 65 and the screw plug 65 also serves to adjust the tension of the spring 64 and thus to determine the pressure within the hydraulic cylinder required to open the safety relief valve 62. A passageway 66 connects the cavity 64 with the annular chamber 49 extending around the hydraulic cylinder.

A pressure gage outlet 67 (Fig. 13) is also located in the bottom of the hydraulic cylinder and connects with a gage pipe 68 which extends to some convenient location on the press housing where the pressure gage 69 is mounted.

The interior of the hydraulic cylinder and the annular chamber 49 about the cylinder are also connected by a passageway 70 controlled by a manually operable needle valve 71 (Fig. 14). The needle valve 71 is normally kept closed, but may be opened to permit hydraulic fluid to escape from the hydraulic cylinder when it is desired to lower the pressure within the same or to lower the cap 50. A further passageway 72 connects the annular chamber 49 with the inlet channel 59 (Fig. 12). Thus hydraulic fluid may be drawn from the annular chamber or reservoir 49 through the passageway 72 and channel 59 into the hydraulic chamber but hydraulic fluid cannot pass from the hydraulic chamber unless the needle valve 71 is opened or unless sufficient pressure is developed with the hydraulic chamber to open the safety relief valve 62. Instead of the annular chamber 49 another suitable reservoir could of course be similarly connected with the hydraulic cylinder.

An air exhaust channel 73 is located in the top of the hydraulic piston 21. This channel 73 is normally kept closed by a screw plug but may be opened occasionally to exhaust any air which might collect in time within the hydraulic cylinder.

Since a reserve of hydraulic fluid is maintained in the annular chamber 49 the action of the spring 57 causes the hydraulic piston 21 to be pushed upward to the extent permitted by the piston-adjusting cap 50 and will cause hydraulic fluid to be drawn into the hydraulic cylinder through the passageway 72 and channel 59 to keep the cylinder filled with hydraulic fluid and thus hold the piston in position. Subsequent 50 downward pressure on the piston will be resisted not only by the spring 57 but also, as long as the needle valve 71 remains closed, by the non-compressible hydraulic fluid in the cylinder. However, should such downward pressure on the piston become too great, the pressure relief valve 62 will be forced open allowing some of the hydraulic fluid to pass back into the annular chamber 49.

Preparatory to the operation of my press the approximate maximum height to which it is desired to have the plunger head rise in pressing the paper against the die or plate is determined. This can be done by having the die or plate in the forward printing position previously mentioned, by having the cam 37 and toggle members 18 and 19 in the full line position shown in Fig. 4 and then turning the hand wheel 55 until the top of the plunger head is properly adjusted with respect to the die or plate. My press is then ready for operation. If it is found from the first one or two sheets which are printed that the paper is not being held against the die with sufficient pressure this condition is quickly remedied by turning the hand wheel 55 so as to 70

raise the cap 50 and therewith permit the piston 21 to be adjusted upwardly. This is done when the plunger is in lowered position. On the other hand, if the piston has been raised too high, thus causing excessive pressure to be exerted by the plunger head this can be quickly relieved by momentarily opening the needle valve 71 and turning the hand wheel 55 in the opposite direction. Should the operator be careless in permitting the piston 21 to be adjusted too high, nevertheless no damage to any part of the press will result since the safety relief valve 62 will prevent such excessive pressure being developed under any condition beyond the predetermined maximum permitted by the relief valve and its adjustable spring 63.

As will be apparent from the foregoing description and explanation, very fine and accurate adjustments are easily possible through the medium of the piston-adjusting cap or hand wheel 55 and thus my invention facilitates the obtaining of most efficient results without excessive trial runs or loss of time, with a minimum of effort and with the dangerous effects of carelessness to a considerable extent reduced.

In order to enable the cap 50 to be raised or lowered to a predetermined position, and therewith cause the maximum height of the plunger head to be at a precise predetermined point, I provide a positioning gage for the cap 50, which positioning gage is shown in Figs. 10 and 11. This gage comprises an indicator arm 90, pivotally mounted at 91 on the lower front plate 89 of the housing so as to swing in a vertical plane. The bottom end of the arm 90 has an off-set, downwardly-extending finger 92 which bears against the top face of the cap 50. A spring 93, set in a recess in the front plate 89, has its upper end secured at 94 and its lower end bears against a pin 95 on the underside of the arm 90 and is so arranged as to exert a constant tendency to swing the arm 90 in counter-clockwise direction (as viewed in Fig. 10). This action of the spring 93 thus holds the finger 92 constantly against the top surface of the cap 50, and movement up or down of the cap (and consequently movement of the hydraulic piston controlled by the cap 50), will cause the arm 90 to move. An indicator scale 96 mounted on the plate 89 adjacent the top end of the arm 90, enables an exact reading of the position of the arm 90 to be made. Thus, with the aid of the scale 96 and the arm 90, the cap 50 (and therewith the plunger head) can be set for any exact predetermined position by manipulation of the hand wheel 55.

This provision for making an accurate predetermined adjustment in my press quickly and easily is another important feature of my invention. For example, it would be possible by using a similar "make-ready" press, to determine the exact desired maximum pressing position for the plunger for printing or embossing with a particular die or plate and for a particular grade of paper. This could all be determined on the "make-ready" press while the main operating press is in use, and then all that is required to set the main press is to adjust the same to the desired position determined on the "make-ready" press.

In the press which I have illustrated and described the die is shown mounted above the plunger. This I consider the preferred arrangement since all the pressure-producing mechanism can be located in the lower part of the housing or below the head, thus making the en-

tire machine more compact. However, it would be possible to have the positions reversed, thus having the plunger in the head with the toggle elements above the plunger and the hydraulic piston and cylinder above the toggle elements. This would correspond to the arrangement generally followed in intaglio presses with the plate below the pressing elements in the head above. My invention could be employed with this arrangement as well as with the arrangement described and illustrated, and it is not my intention to limit my invention otherwise than as set forth in the claims.

I claim:

1. In a press of the character described, an element for producing a desired impression, a plunger located below said element and slideable up and down, upper and lower toggle members, said plunger normally connected with said upper toggle member, said upper and lower toggle members hingedly connected together, means for moving said toggle members alternately towards and away from alinement with each other, a hydraulic cylinder, a hydraulic piston within said cylinder and extending upward from cylinder, means connecting the bottom end of said lower toggle member and the upper end of said piston, a cap on the outside of said cylinder, said piston passing through said cap, limit means associated with said piston and cap to limit the upward movement of said piston with respect to said cap, means for raising or lowering said cap, an inlet valve for hydraulic fluid in the lower portion of said cylinder, a source of hydraulic fluid connected with said inlet valve, a pressure gage connected with said cylinder, whereby the maximum upward travel of said plunger when actuated by said toggle members can be regulated by said cap, and whereby the pressure transmitted through said plunger can be limited to a predetermined maximum.

2. In a press of the character described, an element for producing a desired impression, a plunger located below said element and slideable up and down, upper and lower toggle members, said plunger normally resting on said upper toggle member, said upper and lower toggle members hingedly connected together, cam means for moving said toggle members alternately towards and away from alinement with each other, a hydraulic cylinder, a hydraulic piston within said cylinder and extending upward from said cylinder, means connecting the bottom end of said lower toggle member and the upper end of said piston, a screw cap on the outside of said cylinder, said piston passing through said cap, limit means associated with said piston and cap to limit the upward movement of said piston with respect to said cap, means for turning said cap whereby to raise or lower said cap, an indicator showing the position of said cap and therewith the position of said piston, an inlet valve for hydraulic fluid in the lower portion of said cylinder, a source of hydraulic fluid connected with said inlet valve, a pressure-control safety outlet valve in said cylinder limiting the hydraulic pressure within said cylinder, whereby the maximum upward travel of said plunger when actuated by said toggle members can be regulated by said cap, and whereby excessive pressure transmitted through said plunger can be prevented.

3. In a press of the character described, an element for producing a desired impression, a plunger located below said element and slideable up and down, upper and lower toggle members,

said plunger normally resting on said upper toggle member, a shaft carried by said upper and lower toggle members and attached to said members, a roller mounted on said shaft, a rotating cam, spring means holding said roller against said cam whereby to cause said toggle members to be moved alternately towards and away from alinement with each other, a base block, the bottom end of said lower toggle member pivotally supported on said base block, a hydraulic cylinder, a hydraulic piston within said cylinder and extending upward from said cylinder, said block mounted on the upper end of said piston, a screw cap on the outside of said cylinder, said piston passing through said cap, a shoulder on said piston engageable with said cap, means for turning said cap whereby to raise or lower said cap, an inlet valve for hydraulic fluid in the lower portion of said cylinder, a source of hydraulic fluid connected with said inlet valve, a pressure-control safety outlet valve in said cylinder limiting the hydraulic pressure within said cylinder, means for adjusting said safety valve, whereby the maximum upward travel of said plunger when actuated by said toggle members can be regulated by said cap, and whereby excessive pressure transmitted through said plunger can be limited to a predetermined adjustable maximum.

30 4. In a press of the character described, an element for producing a desired impression, a plunger located below said element and slideable up and down, upper and lower toggle members, said plunger normally resting on said upper toggle member, a shaft carried by said upper and lower toggle members and attached to said members, a roller mounted on said shaft, a rotating cam, spring means holding said roller against said cam whereby to cause said toggle members to be moved alternately towards and away from alinement with each other, a base block, the bottom end of said lower toggle member pivotally supported on said base block, a hydraulic cylinder, a hydraulic piston within said cylinder and extending upward from said cylinder, said block mounted on the upper end of said piston, a screw cap on the outside of said cylinder, said piston passing through said cap, a shoulder on said piston engageable with said cap, means for turning said cap whereby to raise or lower said cap, means for indicating the position of said cap and therewith the position of said piston, an inlet valve for hydraulic fluid in the lower portion of said cylinder, a source of hydraulic fluid connected with said inlet valve, a pressure-control safety outlet valve in said cylinder limiting the hydraulic pressure within said cylinder, means for adjusting said safety valve, a pressure gage connected with said cylinder, whereby the maximum upward travel of said plunger when actuated by said toggle members can be regulated by said cap, and whereby pressure transmitted through said plunger can be limited to a predetermined adjustable maximum.

65 5. In an intaglio printing and embossing press of the character described, a hydraulic cylinder, a piston movable up and down in said cylinder and extending above the top of said cylinder, a toggle assembly mounted on the top of said piston, a plunger supported by said toggle assembly, an element for producing a desired impression supported on said plunger, means for moving the toggle members in said toggle assembly alternately towards and away from alinement with each other, means for delivering hydraulic

11

fluid into said cylinder below said piston, and adjustable limit means connected to said cylinder and engageable by said piston for limiting the upward movement of said piston so as to enable said piston to be hydraulically maintained in a predetermined supporting position.

6. In an intaglio printing and embossing press of the character described, a hydraulic cylinder, a piston movable up and down in said cylinder and extending above the top of said cylinder, a toggle assembly mounted on the top of said piston, a plunger supported by said toggle assembly, an element for producing a desired impression supported on said plunger, means for moving the toggle members in said toggle assembly alternately towards and away from alignment with each other, means for delivering hydraulic fluid into said cylinder below said piston, adjustable limit means connected to said cylinder and engageable by said piston for limiting the upward movement of said piston so as to enable said piston to be hydraulically maintained in a predetermined supporting position, means for adjusting said limit means, and an indicator connected with said limit means.

7. In an intaglio printing and embossing press of the character described, a hydraulic cylinder, a piston movable up and down in said cylinder and extending above the top of said cylinder, a toggle assembly mounted on the top of said piston, a plunger supported by said toggle assembly, an element for producing a desired impression supported on said plunger, means for moving the toggle members in said toggle assembly alternately towards and away from alignment with each other, a coil spring in said cylinder held under compression between the cylinder bottom and the bottom of said piston to urge said piston upwardly, a hydraulic fluid reservoir,

12

a channel leading from said reservoir to the bottom of said cylinder, a one-way valve in said channel causing hydraulic fluid to be drawn into said cylinder by the upward movement of said piston, a pressure-control safety valve outlet leading from said cylinder to said reservoir to permit hydraulic fluid to pass from said cylinder back to said reservoir when the pressure in said cylinder exceeds a predetermined amount, means for adjusting said safety valve outlet, and adjustable limit means connected to said cylinder and engageable by said piston for limiting the upward movement of said piston so as to enable said piston to be hydraulically maintained in a predetermined supporting position.

HOLMES B. GABBERT.
